UNITED STATES PATENT OFFICE.

RUSSELL E. SARD AND HANS P. G. NORSTRAND, OF ALBANY, NEW YORK, ASSIGNEES
TO RATHBONE SARD ELECTRIC COMPANY, INC., OF ALBANY, NEW YORK, A CORPORA-TION OF NEW YORK.

DESIGN FOR A COMBINED KITCHEN-CABINET AND RANGE.

51,048.

Specification for Design.

Patented July 17, 1917.

Application filed May 10, 1917. Serial No. 167,846. Term of patent 14 years.

To all whom it may concern:

Be it known that we, RUSSELL E. SARD and HANS P. G. NORSTRAND, citizens of the United States, residing at Albany, in the county of Albany and State of New York, have invented a new, original, and ornamental Design for a Combined Kitchen-Cabinet and Range, of which the following is a specification, reference being had to the accompanying drawing, forming part thereof.

The figure is a perspective view of a combined kitchen cabinet and range showing our new design.

We claim—

The ornamental design for a combined kitchen cabinet and range as shown.

RUSSELL E. SARD.
H. P. G. NORSTRAND.
